Patented Sept. 30, 1969

215,471

COFFEE POT

Gerald Gulotta, New City, N.Y., assignor to Block China
Company, New York, N.Y., a partnership

Filed Dec. 16, 1968, Ser. No. 15,005

Term of patent 14 years

Int. Cl. D7—01

U.S. Cl. D44—26

FIG. 1

FIG. 3

FIG. 2

FIG. 4

FIG. 6

FIG. 5

I claim:

The ornamental design for a coffee pot, substantially as shown.
